UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

THREAD-CUTTING MECHANISM FOR SEWING MACHINES.

Application filed December 1, 1917. Serial No. 204,870.

To all whom it may concern:

Be it known that I, ALBERT F. FIFIELD, a citizen of the United States, residing at Newark, in the county of Essex and State 5 of New Jersey, have invented certain new and useful Improvements in Thread-Cutting Mechanism for Sewing Machines, of which the following is a specification, reference being had therein to the accompanying 10 drawings.

This invention relates to thread cutting mechanism for sewing machines of the type commonly used for sewing on buttons, tacking and barring operations or the like 15 wherein it is desired to form detached series or groups of fastening stitches.

Of the various thread-cutting mechanisms now known and used, some are too complicated and costly to manufacture. Others 20 employ knives which are so mounted and operated that they will not cut the thread clean unless they are frequently sharpened. Still others will not trim off the threads close to the work and, consequently, the 25 appearance of the finished work is marred by long dangling thread-ends which must subsequently be cut off with a knife or pair of scissors.

The present invention, therefore, has for 30 an object to provide a simplified and otherwise improved thread-cutting mechanism overcoming the above and other defects of prior mechanisms and capable of long continued and efficient operation without attention on the part of the operator.

The invention is preferably embodied in 35 a machine of the well known class 68 Singer type constructed substantially in accordance with the disclosures of the patent to 40 C. M. Horton, No. 807,676, dated December 19, 1905, and patent to G. S. Gatchell, No. 798,130, dated August 29, 1905, and, in the present instance, comprises an unsharpened needle-loop detaining and spreading implement timed to enter and spread the last needle-loop seized by the loop-taker. The 45 throat-plate sustains a stationary cutting-edge which is formed preferably upon a ledger-blade let into or set flush with the 50 under surface of the throat-plate with its cutting edge closely adjacent the usual needle-hole. A cutter-blade is sustained to move with the loop-detainer and spreader and, in the present instance, is formed with 55 a beak adapted to enter the spread needle-

loop and guide the limb thereof which leads to the last stitch within the range of action of the shearing blades. The usual bobbin-thread pull-off, nipping and severing means are provided to sever the bobbin-thread close 60 to the work and to hold the bobbin-thread end while the first few stitches of a new group or series are being formed.

In the accompanying drawings, Fig. 1 is a side elevation of a machine embodying 65 the invention. Fig. 2 is a bottom plan view. Fig. 3 is a bottom plan view in larger scale of the throat-plate and implements mounted thereon. Fig. 4 is a cross-section on the line 4-4, Fig. 3. Fig. 5 is a cross-section on the 70 line 5-5, Fig. 3. Fig. 6 is a detail perspective view of a modification of the invention, and Fig. 7 is a detail perspective view of the shearing blade shown in Figs. 2, 3, 4 and 5. 75

In the preferred embodiment of the invention, as illustrated in Figs. 1 to 5, the machine frame comprises a bed 1, standard 2, bracket-arm 3 and head 4 sustaining the reciprocating needle-bar 5 carrying the 80 eye-pointed needle 6 which cooperates with the usual oscillating shuttle (not shown) sustained in the raceway 7 beneath the bed 1 and actuated by means of the oscillating shuttle-driving shaft 8. Journaled within 85 the bracket-arm 3 is the main-shaft 9 carrying at its forward end the take-up cam-cylinder 10 having the usual peripheral cam-groove 11 which is entered by the following roll 12 carried by the usual take-up 90 lever 13. The front face of the cam-cylinder 10 carries a crank-pin 10' which is connected to the needle-bar 5 by means of the usual pitman 14.

The main-shaft 9 carries at its rearward 95 end the tight and loose pulleys 15 and 16, respectively, to the former of which is secured the usual stopping cam 17 with which the upper end 18 of the stop-motion lever 19 cooperates in a well known manner to 100 stop the machine. As represented in dotted lines in Fig. 1, the main-shaft 9 is provided with a worm 20 meshing with the worm-wheel 21 secured upon the transverse shaft 22 upon which is fixed the controller-cam 105 wheel 23. This cam-wheel is formed with the usual clamp jogging cam-grooves one of which is shown at 24 and is also provided with the usual thread-cutter controlling cam-groove 25.

In the present instance, the invention is shown as embodied in thread-cutting mechanism of the type constructed and operated substantially in accordance with the disclosures in the aforesaid Horton and Gatchell patents, and accordingly, the present mechanism has the usual bobbin or pull-off severing implement or blade 26 formed with the inwardly disposed pull-off edge 27 and 5 with the outwardly disposed up-turned lip 27' which enters the circular groove 28 in the under side of the throat-plate and is formed with a sharpened edge 29 adapted to cut the bobbin-thread.

15 In the present needle-thread severing mechanism use is made of a needle-loop detaining and spreading implement or blade 30 which is preferably shaped substantially the same as the needle-thread cutting blade 38 closed in said Horton patent but differs from said last mentioned blade in that it is not provided with an outer sharpened edge-portion for severing the needle-thread. In the present embodiment of the invention 25 the outer edge 31 of the blade 30 is blunt throughout its extent and said blade serves merely to detain and spread the last needle-loop.

The blades 26 and 30 are fixedly secured 30 as usual to the radial arm 32 projecting from the hub of the sector-gear 33 journaled upon the pin 34 sustained at the under side of the throat-plate p . Secured to the arm 32 is the usual thread-nipper 35 having the 35 hooked extremity 36 adapted to wipe across the needle-hole n and nip the beginning end of the needle-thread drawn down by the shuttle at the beginning of a sewing operation. The arm 32 also has secured thereto, 40 in the present instance, the somewhat resilient shank 37 of a cutting blade 38 which bears yieldingly against the under side of the throat-plate and is formed with a cutting edge 39 adapted to cooperate with the 45 edge 40 of the ledger-blade 41 which is set flush with the under surface of the throat-plate.

The cutter-blade 38 is preferably formed 50 with a beak 42 adapted to enter the spread needle-loop on the detainer blade 30 and positively guide the limb of the needle-loop which leads to the last stitch, within 55 the range of action of the shear cutters 38 and 41. The throat-plate p supports the usual pivoted nipper-lever 43 carrying the 60 nipper-spring 43' having the bifurcated or forked extremity 44 which nips the bobbin-thread as shown in Fig. 5 for the action of the bobbin-thread cutter 29. The lever 43 is formed with a cam-slot 45 which is entered by the pin 46 carried by the arm 47 projecting from the hub of the sector-gear 33. The action of the nipper 43' is disclosed 65 with substantial accuracy in the aforesaid Gatchell patent.

In the modification of the invention shown in Fig. 6 the needle-loop detaining and spreading blade 30 and the needle-thread cutting blade 38 are formed of the same piece of metal; the blade 38 being joined to 70 the blade 30 by the return bend 48 which is made sufficiently light to give the necessary resiliency to the blade 38 so that the latter will bear yieldingly against the under side of the throat-plate. The bending of the blade 38 upwardly also brings it nearer to the under surface of the throat-plate providing for cutting the thread shorter. Whether this blade should, however, be bent upwardly from the spreader 80 depends upon how short it is desired to cut the thread and also depends on the distance the spreader 30 is spaced away from the under surface of the throat-plate. In other words the movable blade formed on 85 the spreader 30 and the ledger-blade edge 40 are so disposed as to effectively cooperate to cut the thread at the desired length. In both modifications it will be noted that the cutting blade or implement 38 and the 90 needle-loop detaining and spreading blade or implement 30 are connected to move as one part.

In the present instance the sector gear 33 is actuated by mechanism substantially as 95 disclosed in said Horton patent and comprising a rack 49 carried by a slide-bar 50 suitably supported beneath the bed-plate 1 and having at its rear end a block 51 formed with a notch 52 entered by the reduced 100 lower end of the lever 53 which is pivotally mounted by means of the stud screw 54 on the bracket 55 (represented in dotted lines in Fig. 1). The lever 53 is provided at its 105 upper end with a follower stud 56 entering the cam-groove 25 of the controlling cam-wheel 23. The block 51 carries at its rear end a pin 57 engaged by the forked arm 58 of a bellcrank-lever mounted on the fulcrum stud 59 and having a rearwardly extending 110 arm 60 provided with an endwise yielding pin 61 normally pressed outwardly by means of the spring 62. The stop lever 19 has an extension 19' below its fulcrum point formed with an aperture 63 which is adapted to be 115 entered by the yielding pin 61 when the stop-lever is in stopping position wherein its upper extremity 18 is in operative relation with the stopping cam 17.

The thread cutter cam groove 25 is so 120 formed that, in the drawing up of the needle-thread loop for the stitch next preceding the last timed stitch, the sector gear 33 receives the first stage of its operative movement which advances the point of the 125 lower or bobbin thread cutting blade 26 beyond the needle hole of the shuttle race cover plate so as to draw aside and pull off the bobbin thread and insure the proper lead of the same without interference with 130

the subsequently acting hooked needle-thread nipper 35. At about the time the needle completes its final descent the stop-lever 19 is tripped into engagement with the stopping cam 17 by the usual connection with the controller cam 23, after which the momentum of the moving parts causes a continued partial rotation of the main-shaft 9, during which the sector gear 33 receives 10 the second stage of its actuation to enter the point of the needle-loop detainer and spreader 30 within the final needle-thread loop; the later throw of the stop-lever producing through the bellcrank-lever 58, 60 15 the final jog of the slide-bar 50 to produce the final thread-cutting action of the cutter-blades 27' and 38. At the start of a new sewing operation the sector gear 33 receives a slight retrograde movement after the first 20 descent of the needle to retract the hooked nipper blade 35 into clamping engagement with the free end of the needle-thread drawn down to the loop taker to hold said end during the production of a few fastening 25 stitches, after which the cutter-blades and nipper are wholly retracted into inoperative relation preparatory to a succeeding thread cutting movement.

While I have shown and described the invention as embodied in a certain well known type of thread-cutting mechanism it is to be understood that the invention is susceptible of embodiment in various other types of thread-cutting mechanism and is otherwise susceptible of material modification both in the form and arrangement of the various parts within the scope of the invention.

Having thus set forth the nature of the invention, what I claim herein is:—

1. In a sewing machine, the combination with a reciprocating needle, a loop-taker and a throat-plate having a needle-hole and supporting a thread-cutting edge closely adjacent said needle-hole, of a needle-loop detaining implement and a shear-cutter including a cutting blade in fixed relation to said needle-loop detaining implement and adapted to coact with said thread-cutting edge to shear off one limb of the detained needle-loop at a point substantially flush with the under surface of the throat-plate and means for moving said implement and cutting blade to detain the needle-loop and shear off one limb thereof.

2. In a sewing machine, the combination with a reciprocating needle, a loop-taker, and a throat-plate having a needle-hole, of a needle-loop detaining implement, and a shear cutter including shearing elements having cooperating cutting edges, one of said elements being so constructed and arranged that its cutting edge is located substantially flush with the under surface of the throat-plate and closely adjacent the needle-hole and the other of said elements being in fixed relation to said needle-loop detaining implement and means for moving the implement to detain the last needle-loop formed at the end of a stitching operation and the second shear-element to shear off one limb of the detained needle-loop.

3. In a sewing machine, the combination with a reciprocating needle, a loop-taker and a throat-plate, of a needle-loop detainer and spreader spaced below the under surface of said throat-plate, and a shear cutter including a resiliently mounted cutter-blade in fixed relation to said needle-loop detainer and spreader and having a cutting edge adapted to bear yieldingly against the under surface of the throat-plate and cut the needle-thread.

4. In a sewing machine, the combination with a reciprocating needle, a loop-taker and a throat-plate, of a needle-loop detainer and spreader spaced below the under surface of said throat-plate, and a shear cutter including a ledger-blade and a cutter-blade in fixed relation to said needle-loop detainer and spreader and having a beak adapted to enter the spread needle-loop and a cutting edge adapted to coact with the ledger-blade to cut one limb only of the needle-loop.

5. Thread-cutting mechanism for sewing machines comprising a movable needle-loop detainer and spreader, a cutter-blade resiliently mounted in fixed relation thereto, and a ledger-blade with which said cutter-blade is adapted to cooperate to shear one limb of the detained needle-loop.

6. Thread-cutting mechanism for sewing machines comprising a movable needle-loop detainer and spreader, a cutter-blade mounted in fixed relation thereto, and having a cutting edge, said cutter-blade being also formed with a beak adapted to enter the detained needle-loop and guide one limb thereof to said cutting edge, and a ledger-blade with which said cutter-blade is adapted to cooperate to shear one limb only of the detained needle-loop.

7. A thread-cutting mechanism for sewing machines comprising a throat-plate having a cutting edge on its under surface, a forwardly and rearwardly movable needle-loop detainer and spreader, and a forwardly directed cutter-blade movable simultaneously with said spreader and coacting with said edge to shear one limb of the needle-loop.

8. A thread-cutting mechanism for sewing machines comprising a throat-plate having a cutting edge on its under surface, a needle-loop detainer and spreader movable parallel thereto, an interposed cutting blade coacting with said edge, and means for guiding one limb of the spread needle-loop across said blade.

9. A thread-cutting mechanism for sewing

machines comprising a ledger-blade, means movable toward and parallel to said blade for detaining and spreading a needle-loop, and a cutter-blade movable simultaneously with said means and in the same direction to coact with said ledger-blade to shear one limb of the detained loop.

10. In a sewing machine having stitch-forming mechanism including a needle and 10 loop-taker, a throat-plate having a needle-hole and supporting a ledger-blade-edge adjacent the needle-hole, a pointed movable implement adapted to enter and spread a needle-loop, a shear-blade in fixed relation to 15 and movable with said implement and adapted to coact with said ledger-blade-edge, and means for moving the implement

to enter and spread the last needle-loop formed in a stitching operation and the shear-blade to shear-cut one limb thereof. 20

11. In a sewing machine the combination with a needle, a loop-taker and a throat-plate, of a movable needle-loop detainer and spreader spaced below the under surface of the throat-plate, a shearing cutter located 25 between the detainer and the work adapted to shear-cut one limb of the needle-loop and including a cutter-blade movable with said needle-loop-detainer and spreader, and means for moving said detainer and spreader and 30 said cutter-blade.

In testimony whereof, I have signed my name to this specification.

ALBERT F. FIFIELD.
